JOSEPH H. JONES, OF WINTHROP, MASSACHUSETTS.

CAP SPINNING FRAME.

Application filed May 31, 1923. Serial No. 642,379.

The invention is an improvement in spinning devices of the live-cap class and has for its general object to provide in improved manner for the mounting and driving of a cap, as well as for the retardation of the cap in its rotation which, through producing a difference in the rates of rotation of the spinning element and the co-operating cap operates as a factor in occasioning the winding of the spun yarn upon the spinning element.

An illustrative embodiment of the invention is shown in Fig. 1 of the drawings, which represents, partly in section, an organization comprising the essentials of the invention. Fig. 2 shows the clutch-device in horizontal section.

Organized spinning devices of the live cap class comprise a cap 1 mounted upon the blade or barrel of a revolving spinning element 2 and revolving in unison with such element, and one or more bearing elements on the order of those shown at 4, 5, coacting with the cap. The revolving spinning element 2 in the drawings is a bobbin, only partly shown, which is mounted upon a spinning spindle 3, only partly shown. The cap is mounted upon the blade or barrel of the spinning element by means of a central hole 11 in the head of the cap, such hole being so proportioned that the wall of the said hole, at the smallest diameter of the hole, has a close but easy sliding fit upon the said blade or barrel. The easy sliding fit permits the cap to gravitate downward upon the said blade or barrel until it is supported by the bearing element or elements (4, 5). It also permits the traverse movements of the cap up and down upon the blade or barrel which are required to take place for the distribution of the spun yarn upon the blade or barrel in being wound thereon. The bearing element or elements has or have been a wheel or wheels, as in the case of the bearing elements shown at 4, 5, and has or have been arranged in different relations for controlling the cap vertically, or laterally, or both vertically and laterally, in different instances. The wheel or wheels, commonly termed pivots or pivot wheels, has or have been revolvably mounted on a support or supports carried by a rail 6 to which in practice vertical traversing movements are given. A convenient form of support for the pivot wheels

4, 5, is represented at 51 in Fig. 1. In the 55 operation of the spinning devices, the yarn being spun passes down alongside the cap and around the edge or lip at the bottom of the cap to the spinning element 2, upon which it is wound. As the rail 6 goes up 60 the cap is raised by the bearing element or elements upward along the blade or barrel of the spinning element. As the rail goes down the cap gravitates downward upon said blade or barrel, following the bearing 65 element or elements downward.

In the case of early instances of live-cap spinning devices the cap was positively revolved in unison with the revolving spinning element, at the same speed as the latter, through the cap being in sliding clutch engagement with the blade or barrel of the spinning element by means of a splined connection, usually a key and groove. The bearing element or elements was or were 70 wheels or disks, with the top or tops of which the cap made contact vertically. In the case of later instances, the splined or key and groove clutch for causing the cap to be positively rotated being retained, the bearing wheels, in addition to being adapted to support the cap vertically, were formed and arranged to operate, through contact with peripheral portions of the cap, to prevent 75 the cap from becoming locked to the blade or barrel of the spinning element in a manner which would interfere with free vertical movement of the cap up and down upon the said blade or barrel in conformity with the 80 up and down movements of the traverse. In 85 all these instances it was found that vibration of the spindle, and other causes, interfered with reliability of action of the cap; and by reason of the cap being revolved at the same rate of speed as the spinning element the cap had no effect in producing retardation of the circling movement of the 90 yarn in being spun, so as to promote the winding of the yarn upon the spinning element, so that various expedients were employed to retard the yarn in its revolution with the spinning element, to cause it to 95 wind upon the latter. In the case of still later instances the splined or key and groove connection has been omitted, and for the 100 purpose of insuring rotation of the cap the bearing element or elements cooperating with the latter has or have been arranged, etc., to cant or tilt the cap slightly relative to 105

the blade or barrel of the spinning element, so as to cause the bearing in the cap head to cramp or bind a little upon said blade or barrel. In the case of a frictionally driven cap 5 this cramping or binding is useful for causing the cap to start promptly into rotation in starting up the spinning frame after a stoppage of the frame, or in starting up the individual spinning element after 10 piecing up a broken end of yarn. The canting or tilting has been occasioned through engagement of the periphery of an external lateral bearing member constituted by a bearing wheel or pivot with the outer 15 side or periphery of the cap near the lower edge of the cap. Thereby the cap has been given a slight tilt away from the lateral bearing member, such tilt operating to bring the lower portion of the central bearing of 20 the cap head into close contact with that side of the spinning element which is adjacent said lateral bearing member, and also operating to cause the spinning element to be frictionally gripped between upper and lower 25 portions of said central bearing. However, canting or tipping of a cap, and resultant cramping or binding of the same upon a spinning element, have the drawback that they clutch or lock the cap to the spinning element in such manner as to prevent the 30 free relative axial movement that is necessary for the distribution of the yarn up and down upon the spinning element, i. e., as the traverse occurs. Such canting or tipping 35 also results in the cap being caused to rotate upon an axis that is slightly inclined with respect to that on which the spinning element rotates, so that the cap rotates out of 40 true concentricity with the blade or barrel of the spinning element. More or less irregularity of action, vibration and chattering, and more or less accidental up and down movement of the cap relative to the spinning element are observed, all of which it is important and advisable to eliminate. Another 45 drawback of the cramping or binding incident to the canting or tipping of the cap relative to the spinning element is the tendency to cause the cap to revolve at the same speed with the spinning element. This interferes with or prevents the retardation of the cap which is necessary to cause it to revolve more slowly than the spinning element so as to secure satisfactory winding action. 50 It is important that the cap should revolve more slowly than the spinning element, in order that the yarn passing around its lower edge to the spinning element may be caused to wind upon the latter.

60 The general object of the invention is to provide live cap devices which will operate satisfactorily without cramping or binding of the cap upon the spinning element resulting from canting or tipping the cap relative to the axis of the spinning element, and

which in operation will secure proper and satisfactory performance of the important functions of so-called pivots or pivot-wheels, namely (1) neutralizing the tendency of the cap and spinning element to become locked together by centrifugal action so as to prevent one thereof from moving axially with respect to the other; (2) effecting in the case of caps which are driven by frictional engagement a sufficient retardation of the speed of rotation of a cap to cause the winding of the yarn, as it is spun, upon the spinning element; and (3) governing the position of the cap vertically during the traverse movements by which the yarn that is in process of being spun and wound upon the bobbin is distributed along the said blade or barrel.

In accordance with the present invention I form in the head of cap 1 a central bore or hole 11 which flares downwardly and is of such dimensions as to permit of a considerable inclination of the axis of the cap relative to the axis of the spinning element 2 without such contact with the periphery of the spinning element as to produce cramping or binding. As in Letters Patent No. 1,385,078 granted July 19, 1921, and No. 1,401,705 granted Dec. 27, 1921, the cap 1 has its periphery cone-shaped and upwardly flaring, for coaction of the coacting flaring periphery with the periphery of the so-called pivot or pivot-wheel 5 aforesaid, which constitutes a lateral bearing element for the cap. The second so-called pivot-wheel 4 is mounted opposite the pivot 5, to revolve upon an upright axis in connection with the support 51 for the two pivots or pivot-wheels, such support being mounted as aforesaid upon a supporting rail 6. This second pivot-wheel has a beveled periphery, tapering upwardly, upon which the lower edge or lip of the cap rests more or less lightly. The two pivot-wheels jointly serve in affording vertical support to the cap. The arrangement of the pivot-wheels 4 and 5 with relation to the spinning element and cap is such that while the parts are motionless the cap will be supported vertically by the pivot-wheels without cramping or binding of the cap upon the barrel or blade of the spinning element. For the driving of the cap I utilize either light frictional contact between the blade or barrel of the spinning element with the upper portion of the interior surface of the bore or hole 11 through the cap-head, or, preferably, the light clutching action of the contact-means of a friction clutch provided in connection with the cap-head. I prefer the employment of a friction clutch on the order of that of my Letters Patent No. 1,445,291, granted Feb. 13, 1923, for improvements in cap spinning frames, comprising a plurality of contacts symmetrically disposed around the axis 136

of revolution, as for instance in the case of the balls 7, 7, of the ball-clutch illustrated in the drawings. The said balls in the drawings are gently pressed inward into contact with the blade or barrel of the spinning element by means of encircling band springs 8, 8.

The mode of operation is as follows:

The spinning element being at rest the cap is sustained vertically by its edge or lip resting upon the beveled peripheral surface of pivot-wheel 4, and by the contact of the flaring periphery of the cap with the pivot-wheel 3. By the support afforded by the two pivot-wheels acting conjointly, the cap is sustained in an upright intermediate position, without cramping or binding upon the blade or barrel of the spinning element. As the spinning element begins to rotate, the frictional contact between the blade or barrel thereof and the interior surface of the bore or hole in the cap-head, or the light clutching action of the ball-clutch, causes the cap to turn with the spinning element. Contact of the cap with the respective pivot-wheels operates to retard the rotation of the cap, for the purpose of causing the yarn to wind upon the spinning element as fast as spun, and in accordance with the rate of delivery of the roving from the usual front rolls. The contact of the flaring periphery of the cap with the periphery of the radially-disposed pivot-wheel 5 acts with a tendency to lift the cap slightly so as to relieve the bevel pivot-wheel 4 from carrying the weight of the cap, which reduces the wear which would necessarily come from the edge or lip of the cap resting entirely upon the beveled surface of pivot-wheel 4.

The tendency of the cap in relation to the beveled pivot-wheel 4 is to run or ride on the lower portion of the bevel. This tendency acts to crowd the cap lightly into contact with the periphery of the radially-disposed pivot-wheel 5. The contact of the flaring periphery of the cap with the radially-disposed pivot-wheel 5 acts to crowd the cap reversely toward the bevel pivot-wheel 4. Any pressure of the cap acting against pivot-wheel 5 will tend to force the edge or lip of the cap against the beveled surface of pivot-wheel 4, thus causing it to ride on a higher part of the bevel. The conjoint action is to resist slightly the rotation of the cap, thus checking or retarding the rotation of the cap in an improved manner.

The increased flare of the inside bearing of the cap-head allows more side-play of the lower portion of the cap, and without any positive clutching of the cap to the blade or barrel of the spinning element but with resulting increased interference between the cap and the two opposing pivot-wheels. That is to say, the flaring hole in the cap-head permits a sufficient amplitude of

swinging or tilting of the cap without increased binding or cramping of the cap to the spinning element. The said interference is on the order of a braking action in which the two pivots exert a tendency to retard the rotation of the cap. Such braking action is applied externally.

One bevel pivot 4 is employed to each cap.

The driving action between the blade or barrel of the spinning element and the cap is such as to be effective, after the stopping of the spinning element, to cause the cap to start up in unison with such element in restarting the latter. The braking or interfering action of the two pivot-wheels 4 and 5 operates thereafter to effect the retardation of the cap which ensures the winding of the yarn, as spun, upon the spinning element 2.

The ball-clutch devices shown in the drawings comprise two circular series of balls, one above the other, in an annular ball-container 9, as in my application filed Dec. 26, 1922, Serial No. 608,809, the said balls tending radially outward under the influence of centrifugal force, after the cap has assumed sufficient speed of rotation, so that during the regular running of the spinning frame in which the devices are employed the cap is driven chiefly by light frictional action. The circular arrangement of the two series of balls causes the clutch devices to act uniformly around the spinning element, and with a tendency to centralize the cap into concentricity with the spinning element, without canting or cramping of the cap.

What is claimed as the invention is:—

1. In live-cap spinning devices, the combination with a rotatable spinning element, of a live cap driven by light frictional engagement with the blade or barrel of said element, having a bore in the cap-head permitting the cap to assume its normal positions when at rest and in motion without cramping or binding upon said blade or barrel, and oppositely-located pivot-wheels coacting to sustain the cap while in active rotation with its axis uni-directional with that of the spinning element and its bell-shaped portion in an intermediate position substantially concentric with the axis of the spinning element whereby cramping or binding interfering with free vertical relative movement is obviated.

2. In live-cap spinning devices, the combination with a rotatable spinning element, of a live cap having a bore in the cap-head permitting the cap to assume its normal positions when at rest and in motion without cramping or binding upon the blade or barrel of the spinning element, contact-means providing for light frictional driving engagement between said blade or barrel and the cap, and oppositely acting pivot-wheels

coacting to sustain the cap while in active rotation with its axis uni-directional with that of the spinning element and its bell-shaped portion in an intermediate position substantially concentric with the axis of the spinning element whereby cramping or binding interfering with free vertical relative movement is obviated.

3. In live-cap spinning devices, the combination with a rotatable spinning element, of a live cap having a bore in the cap-head permitting the cap to assume its normal positions when at rest and in motion without cramping or binding upon the blade or barrel of the spinning element, a plurality of contacts symmetrically disposed around the axis of revolution providing for light frictional driving engagement between said blade or barrel and the cap, and oppositely acting pivot-wheels coacting to sustain the cap in an intermediate position substantially concentric with the axis of the spinning element.

4. In live-cap spinning devices, the combination with a rotatable spinning element, of a live cap having a bore in the cap-head permitting the cap to assume its normal positions when at rest and in motion without cramping or binding upon the blade or barrel of the spinning element, and a ball-clutch device having its contact-elements symmetrically disposed around the axis of revolution and providing for light frictional driving engagement between said blade or barrel and the cap, and oppositely acting pivot-wheels coacting to sustain the cap in an intermediate position substantially con-

centric with the axis of the spinning element.

5. In live-cap spinning devices, the combination with a rotatable spinning element, of a live cap driven by light frictional engagement with the blade or barrel of said element, the said cap having an upwardly flaring periphery and also having a bore in the cap-head permitting the cap to assume its normal positions when at rest and also when in motion without cramping or binding upon said blade or barrel, a pivot-wheel in radial engagement by its periphery with the flaring periphery of the cap, and an oppositely-located pivot-wheel having a bevel upon which the edge or lip of the cap rests, said two pivot-wheels cooperating in supporting the cap vertically. 55

6. In live-cap spinning devices, the combination with a rotatable spinning element, of a live cap having an upwardly flaring periphery and also having a bore in the cap-head permitting the cap to assume its normal positions when at rest and also when in motion without cramping or binding upon said blade or barrel, a light frictional driving device acting concentrically and tending to rotate the cap in unison with the spinning element, a pivot-wheel in radial engagement by its periphery with the flaring periphery of the cap, and an oppositely-located pivot-wheel having a bevel upon which the edge or lip of the cap rests, said two pivot-wheels cooperating in supporting the cap vertically. 60 65 70

ROBERT BURGESS.
